UNITED STATES PATENT OFFICE

106,551

DESIGN FOR A DRESS

Philip Wenett, New York, N. Y.

Application August 23, 1937, Serial No. 71,233

Term of patent 3½ years

To all whom it may concern:

Be it known that I, Philip Wenett, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design consists in the arrangement of beaded felt floral elements and embroidered leaves brought together by ribbon bows at the neckline and on the skirt.

I claim:

The ornamental design for a dress, substantially as shown and described.

PHILIP WENETT.
